(57) **CLAIM**

The ornamental design for a scooter, as shown and described.

DESCRIPTION

FIG. 1 is a top, front, right side perspective view of a scooter;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and

FIG. 8 is a bottom plan view thereof.

FIG. 9 is an enlarged view of area "9" indicated in FIG. 1;

FIG. 10 is an enlarged view of area "10" indicated in FIG. 1;

FIG. 11 is an enlarged view of area "11" indicated in FIG. 1; and,

FIG. 12 is an enlarged view of area "12" indicated in FIG. 2.

The short evenly spaced broken lines in the figures depict portions of the scooter that form no part of the claimed design. The long evenly spaced broken lines around the enlargement areas in FIGS. 1-2 and 9-12 are shown for the purpose of illustrating the bounds of the enlargements and form no part of the claimed design.

1 Claim, 12 Drawing Sheets
